UNITED STATES PATENT OFFICE

2,484,884

HYDRAULIC TRANSFORMER

John C. Hanna, Chicago, Ill., assignor to Hanna
Engineering Works, Chicago, Ill., a corporation
of Illinois

Application June 10, 1946, Serial No. 675,566

12 Claims. (Cl. 103—51)

1

The invention relates to hydraulic pressure boosters and has reference in particular to an improved device of this character which will transform a low pressure liquid into a high pressure liquid and wherein the reduction in volume of the high pressure liquid will be inversely proportional to the increase in pressure.

An object of the invention is to provide a combination pump and motor device of the differential piston type which will operate on a liquid of a low pressure to raise a predetermined portion of said low pressure liquid to a higher pressure, which will be compact, embodying a minimum of operating parts, and wherein said parts will be contained in a single unit of leak-proof construction.

Another object of the invention is to provide a hydraulic transformer of the character described which will incorporate a novel distributor valve for controlling the flow of low pressure liquid to the differential piston which operates as a pump of constant displacement.

A more specific object resides in the provision of a hydraulic transformer incorporating a distributor valve of the rotating type and which valve is hydraulically balanced by the balanced oil pressure acting upon it.

Another object of the invention is to provide a hydraulic transformer wherein the selector or rotating distributor valve in controlling the flow of the low pressure liquid to the differential piston will produce four pumping strokes of said piston per revolution.

Another object is to provide an improved hydraulic transformer incorporating a rotating distributor valve which will require the minimum in power to rotate it since the same is hydraulically balanced and which transformer will deliver a constant flow of high pressure liquid, the volume of which compared to the volume of low pressure liquid entering the device will be inversely proportional to the boost in pressure.

With these and various other objects in view, the invention may consist of certain novel features of construction and operation as will be more fully described and particularly pointed out in the specification, drawings and claims appended hereto.

In the drawings which illustrate an embodi-

2

ment of the invention, and wherein like reference characters are used to designate like parts—

Figure 1 is a longitudinal sectional view taken substantially centrally of the hydraulic transformer of the invention showing the rotary distributor valve and the differential piston;

Figure 2 is a transverse sectional view taken substantially along line 2—2 of Figure 1;

Figure 3 is a transverse sectional view taken substantially along line 3—3 of Figure 1;

Figure 4 is an end view of the hydraulic transformer looking in the direction of the arrows on line 4—4 of Figure 1;

Figure 5 is an end view of the auxiliary piston assembly;

Figure 6 is a longitudinal sectional view of the auxiliary piston assembly;

Figure 7 is a schematic arrangement illustrating the operating parts of the present hydraulic transformer, their relation with each other, and the complete hydraulic circuit for their operation;

Figure 8 is another view illustrating the arrangement of the various devices and their connection as may be required for a complete hydraulic circuit for the transformer; and

Figure 9 is a transverse sectional view taken substantially along line 9—9 of Figure 1.

Referring to the drawings, and in particular to Figures 1 and 8, the hydraulic transformer of the invention is shown as including a unitary housing 10 which contains all the operating parts of the device and which is composed of several units including a central unit 11, an inlet unit 12, an outlet unit 13 and a bearing unit 14. The inlet and outlet unit are bolted to opposite sides of the central unit by the securing screws 15 shown in Figures 2 and 3 and the bearing unit is secured to 12 by the screws 16, as shown in Figures 1 and 4.

The housing 10 which operates as a pressure booster is connected in the hydraulic circuit as disclosed in Figure 8, wherein the reservoir is indicated by numeral 17 and the low pressure oil pump 18 is suitably associated therewith as by being supported on top of the reservoir. An oil inlet line 20 extends from within the reservoir 17 to the inlet side of the pump 18 which is driven by motor 21, the shaft 22 of the motor providing a sprocket 23 and connecting with the shaft 24

50

of the pump by means of the coupling unit 25. A relief valve 26 is connected in line 27 from the pump and which supplies low pressure oil to the auxiliary piston assembly 28 to be described in detail as the description proceeds. The low pressure oil leaves the assembly 28 by line 30 which comprises the inlet for the hydraulic transformer 10, the inlet line 30 connecting with 10, as best shown in Figure 1. The hydraulic transformer is provided with two outlets, one a low pressure outlet and the other a high pressure outlet. The former is indicated by the line 31 and which returns the low pressure oil from the transformer back to the reservoir. The high pressure line 32 leads from the outlet unit 13 of the hydraulic transformer, as clearly evident from Figure 1, and is provided with the T connection 33, one end of which is associated with the auxiliary piston assembly 28.

The operating shaft 34 of the hydraulic transformer is provided with sprocket 35, Figure 8, and this sprocket is driven by sprocket 23 by means of an endless chain operatively connecting the said sprockets so that the motor 21 comprises the source of power for the low pressure pump and the transformer and which two devices are driven in unison.

Shaft 34 is journaled by the bearing member 14 of the transformer, the ball bearing assembly 36 being provided for substantially frictionless rotation and the inner end of said shaft being reduced to form the key 37 which interlocks with the adjacent end of the rotating distributor valve 38. Said valve is cylindrical in general form and is suitably journaled for rotation by the housing 10. At the inlet end of the distributor valve an internal passage 40 is formed having openings 41 which communicate with the chamber 42 connecting with the inlet conduit 30 so that low pressure oil is supplied to passage 40, the same entering through the openings 41 as the valve rotates. At the opposite end of passage 40 a pair of outlet ports 43 are located, the same being positioned diametrically of the distributor valve 38. In accordance with the invention the diametrical outlet ports are adapted to align with certain conduits or passages formed in the housing and which conduct the low pressure oil to the differential piston, which structure will be presently described in detail.

Referring again to the distributor valve, the outlet end of the same is also provided with an internal passage 44 having openings 45 which communicate with the chamber 46 connecting with the outlet 31. The low pressure oil from said passage 44 is accordingly discharged through openings 45 and the same leaves the housing 10 by the outlet line 31. The passage 44 also has a pair of ports 47 which, as regards this end of the valve, function as inlet ports, the same being positioned diametrically and aligning with certain conduits or passages in the housing, which conduct the low pressure oil from the differential piston. The diametrical position of the outlet ports 47 transversely of the valve 38 is at right angles to the inlet ports 43, Figure 7.

The differential piston is located within the housing below the valve 38 and includes a center piston 48 of large diameter positioned within the chamber 50 and having reciprocating movement in said chamber from end to end since the chamber has a length somewhat greater than that of the piston 48. An extension is provided on each end of piston 48 and these form the high pressure

pistons, the one on the right hand end, Figure 1, being indicated 51, and the piston on the left hand end being indicated 52. It will be seen that the high pressure pistons are much smaller in diameter than the center or low pressure piston, the ratio of their diameters determining the pressure ratio between the low and high pressure oil. For example, if the high pressure pistons have a diameter and thus an area which is one-fifth that of the large piston, then the high pressure oil will have a pressure which is approximately five times that of the low pressure oil. However, the volume of the high pressure oil will be one-fifth of that of the low pressure oil delivered to the transformer. It will be seen that the chamber 50 for piston 48 is provided by the central unit 11. The inlet unit 12 provides a chamber 53 for the high pressure piston 51, whereas, the outlet unit 13 in a similar manner provides chamber 54 for the high pressure piston 52, Figure 7. Cushioning or shock absorbing members 55 are located at the respective ends of the chamber 50 to cushion the movement of the piston 48 at each end of its stroke, the members being backed by the coil springs 56.

Chamber 53, accommodating the high pressure piston 51, has communication with a vertical bore 57, Figure 1, formed in the inlet unit 12 of the device. This bore has connection with a duct which will be presently described by which it is supplied with low pressure oil and for controlling the inlet of this low pressure oil to chamber 53 the vertical bore is equipped with an insert 58 containing a ball check valve 60 which opens to admit the low pressure oil and closes to prevent its flow except through openings 61 which deliver into chamber 53 where the low pressure oil acts against piston 51 and is in turn acted on by said piston.

The base of vertical bore 57 is somewhat enlarged to receive another insert 62 providing the ball check valve 63, which, however, opens downwardly to admit high pressure oil from above and closes to prevent its flow except through openings 64 in the said insert and which thus delivers the high pressure oil to a longitudinal passage or duct 65 having communication with the ball valve 63 through said openings. The ball check valves 60 and 63 are so constructed and tensioned by their associated coil springs that valve 60 will open when subjected to low pressure oil and valve 63 will open only when subjected to high pressure oil.

The outlet unit 13 is likewise provided with a vertical bore 66, similar to 57, and which has connection with a duct to be described, by which the bore is supplied with low pressure oil at definite times in the rotary movement of the distributor valve 38. For controlling the inlet of this low pressure oil to chamber 54 the vertical bore is equipped with an insert 67 providing the ball check valve 68 which opens to admit said oil and closes to prevent its back flow so that the oil flows out through openings 69 into chamber 54 where it acts on piston 52 and is in turn acted on by said piston. The base of vertical bore 66 is enlarged to receive another insert 70 providing ball check valve 71. The valve 71, however, opens downwardly to admit high pressure oil from above and closes to prevent flow except through openings 72 in the insert. The oil flowing through openings 72 is admitted to the duct 65 communicating therewith and the said duct 65 extends through and beyond the vertical bore 66 to connect with the vertical passage 73 comprising

ing the high pressure oil outlet of the hydraulic transformer. This outlet connects with the high pressure oil line 32, as shown in Figure 1. As regards the ball check valves 68 and 71, it is also understood that they are constructed and tensioned by their coil springs to open when subjected to low pressure oil and high pressure oil, respectively.

The various ducts or passages provided by the hydraulic transformer and which conduct low pressure oil from the distributor valve 38 to the respective ends of the differential piston will now be described. These ducts are best shown in the schematic arrangement of Figure 7. The central unit 11 of the device adjacent the end toward the inlet unit 12 is formed with a long vertical duct 74 and a short vertical duct 75, the same being positioned on opposite sides of the longitudinal center of the device. Both ducts 74 and 75 have openings 76 and 77, respectively, communicating with the right hand end of chamber 50, Figures 1, 2 and 7. The vertical duct 74, which extends above the distributor valve on the right hand side of the same, Figure 2, connects at its upper end with a horizontal duct 78, and said duct in turn connects with an inlet passage 80 and an outlet passage 81, the same having an inclination of about forty-five degrees and extending to the distributor valve 38. It will be understood that the passages 80 and 81 are positioned so as to align with the ports 43 and 47 spaced lengthwise of the distributor valve. The vertical duct 75 connects at its upper end with a horizontal duct 82 which at one end connects with an inlet passage 83 and an outlet passage 84. The passages 83 and 84 extend to the distributor valve and the same are positioned to align with ports 43 and 47, respectively. Also said passages have a forty-five degree inclination and are substantially in opposed relation to passages 80 and 81 previously mentioned. The opposite end of horizontal duct 82 has connection with a vertical duct 85 forming an extension of the same and which duct communicates with the vertical bore 57, Figures 1 and 4.

A similar arrangement of ducts and passages are provided for the left hand end of chamber 50, as will be clear from Figures 3 and 7. The long vertical duct 86 and the short vertical duct 87 are reversed with respect to the ducts 74 and 75. However, openings are formed at their lower ends, indicated by numerals 88 and 89, respectively, and which communicate with the left hand end of chamber 50. The long vertical duct 86 connects at its upper end with a horizontal duct 90, which in turn connects with an inlet passage 91 and an outlet passage 92, the passages aligning with the ports 43 and 47 and extending to the distributor valve. The short vertical passage 87 on the opposite side of the distributor valve 38 has connection at its upper end with a horizontal duct 93 which at one end connects with an inlet passage 94 and an outlet passage 95. These passages are inclined forty-five degrees and extend to the distributor valve, being aligned with ports 43 and 47 and in substantial opposed relation with 91 and 92. It will also be observed that each set of inlet and outlet passages are disposed around the distributor valve in spaced relation of approximately ninety degrees so that with each quarter turn of the valve a different set of passages are aligned with the inlet and outlet ports 43 and 47. The end of the horizontal duct 93 has connection with a duct 96 which leads in

a downward direction similar to 85 and communicates with the vertical bore 66.

This completes the arrangement of ducts and passages connecting the distributor valve with the differential piston in accordance with the invention and the operation of the parts for each half revolution of the valve will be explained.

Referring to Figure 7, it will be understood that low pressure oil from line 30 will have entered the distributor valve 38, that is, the inlet passage 40 of the valve through openings 41, and assuming the valve to be positioned, as shown in Figure 7, the low pressure oil will be delivered by ports 43 to the inlet passages 80 and 83 which are aligned with the ports. This flow of oil is conducted by the ducts 74 and 75 to the right hand end of chamber 50, the same entering this end of the chamber through the openings 76 and 77, respectively. The piston 48 is located at the right hand end of chamber 50 and thus the low pressure oil acts on the piston to cause it to move in a direction toward the left. The oil is also conducted by ducts 82 and 85 to the vertical bore 57, the oil entering the insert 58 through the check valve 69 which opens to admit flow of the oil in this direction. As previously explained, this low pressure oil will enter chamber 53 and act on piston 51 so that the full area of the differential piston is subjected to pressure exerted by the low pressure oil and it accordingly moves to the left end of chamber 50.

As piston 48 moves to the left the oil in chamber 50 in front of piston 48 is caused to flow out through the openings 88 and 89 into ducts 86 and 87 which deliver the oil to the outlet passages 92 and 95. These passages, at this instance in the rotary movement of the valve 38, are in alignment with the ports 47 so that the oil enters the valve 38 and subsequently is delivered to the outlet 31 which returns this low pressure oil to the reservoir, Figures 7 and 8.

The oil in front of the high pressure piston 52 is acted on by said piston as the same moves toward its extreme left hand position and this oil is compressed to a high pressure. Assuming the area of piston 52 to be one-fifth of the cross-sectional area of piston 48, then the oil will be increased in pressure five times that of the low pressure oil but its volume will be only one-fifth of the volume of oil acting on the differential piston and causing it to move to the left and compress the oil to its high pressure. This high pressure oil from chamber 54 is caused to flow into insert 70 through the ball check valve 71 which opens to admit said oil flow and which is delivered to the outlet 73 and thus to the high pressure line 32.

The differential piston remains in position at the left end of chambers 50 and 54 as the rotary valve 38 continues to rotate and upon rotation of approximately ninety degrees the ports 43 align with the inlet passages 91 and 94 so that low pressure oil is delivered to these passages. Since said passages connect with the ducts 86 and 87 the low pressure oil is admitted by openings 88 and 89 to the left end of chamber 50 where it acts on piston 48 to cause the piston to move to the right. The oil is also conducted by ducts 93 and 96 to vertical bore 66 and it enters insert 67 through the ball check valve 68 which opens to admit flow in this direction. From the insert the oil enters the chamber 54 to act on piston 52 to augment the action of the oil on piston 48.

As the differential piston moves to the right the oil in front of piston 48 is returned to ducts 74 and 75 and delivered to outlet passages 81 and

84 which at this instance are in alignment with the ports 47. This low pressure oil enters the passage 44 in the valve 38 and is eventually delivered to line 31 and returned to the oil reservoir. The oil in front of piston 51 is compressed to the high pressure, as previously explained, and is forced to enter insert 62, the ball check valve 63 opening to admit this flow of high pressure oil. From the insert 62 the oil is delivered to duct 65 and then to outlet 73 and to the high pressure line 32.

The differential piston remains in position in the right hand end of chambers 50 and 53 as the rotary valve 38 continues its rotation. Upon another ninety degree turn of the valve the ports 43 will be caused to again align with inlet passages 60 and 83 and the ports 47 with outlet passages 92 and 95. The operation first described is thus repeated and the differential piston will be moved to the left as has been described to compress the oil in front of piston 52. Thus the valve 38 in rotating one hundred and eighty degrees has produced two strokes of the differential piston, or, in other words, two pumping strokes for high pressure oil. For a full revolution of the valve it follows that four pumping strokes of the differential piston result.

From the foregoing it will be understood that the distributor valve 38 functions as a control member for directing the flow of low pressure oil to the differential piston. For each ninety degree rotative position of the valve certain inlet passages are supplied with low pressure oil from line 30 and certain outlet passages are connected to the outlet line 31 for discharge of low pressure oil. The fluid medium which is elevated to the high pressure for which the device is designed is acted on by the small diameter pistons 51 and 52. In the first instance this medium at low pressure does its share of work in reciprocating the differential piston and then the same fluid medium is acted on by the piston being compressed to the high pressure and eventually discharged through the outlet line 32.

The rotary distributor valve 38 requires very little power since the valve is hydraulically balanced by the balanced oil pressure acting on it. Flow into the valve takes place symmetrically through the openings 41 and is discharged in a similar manner through openings 45. Also the arrangement of the ports 43 and 47 is symmetrical so that the outflow and inflow of the low pressure medium is balanced and the load on the valve is a minimum.

The hydraulic transformer delivers the high pressure oil by the to and fro strokes or reciprocations of the double ended differential piston. As the said piston moves in one direction, due to low pressure oil behind it, the high pressure piston on the forward end is compressing oil to a high pressure. It follows that when the differential piston reaches the end of its stroke in one direction, the flow of both high and low pressure oil will momentarily cease. If it were not for the auxiliary piston assembly 28, Figures 5, 6, 7 and 8, the low pressure oil would rise in pressure if the latter exceeds the pressure resistance opposed against this flow and the high pressure oil would drop in pressure. As the low pressure oil tends to rise in pressure between strokes of the differential piston, the large end 98 of the auxiliary piston is acted on by this now slightly higher low pressure oil. Said low pressure oil, due to its somewhat higher pressure, acts on the large end 98 of the auxiliary piston to move the piston

in a direction toward the right, Figure 6, causing the coil spring 100 to be compressed and the small piston end 101 to displace an amount of oil sufficient to augment the high pressure oil in lines 32 and 33, which has ceased to flow from the transformer.

The auxiliary piston will function at each reversal in the movement of the differential piston. The area ratio of the large piston end 98 and the small piston end 101 is actually the same as the area ratio of the differential piston. The function of the coil spring 100 is to return the piston 98 to its normal position, as shown in Figure 6, after it has made the movement as described, which is necessary to assure even flow of high pressure oil during reversals in the strokes of the differential piston.

The invention is not to be limited to or by details of construction of the particular embodiment thereof illustrated by the drawings as various other forms of the device will of course be apparent to those skilled in the art without departing from the spirit of the invention or the scope of the claims.

What is claimed is:

1. In a hydraulic booster, a housing member having an inlet passage connecting with a source of fluid pressure, an exhaust passage connecting with an exhaust line, and a high pressure delivery line connecting with an outlet passage for a high pressure fluid, a differential piston within the member mounted thereby for reciprocating movement, said differential piston including a main operating piston having reciprocating movement within a chamber provided therefor by said member and ram pistons extending from each end of the main piston and which move in chambers respectively also provided by said member, a passage in the member associated with each ram piston chamber at the end thereof and connecting with said outlet passage, a distributor valve journaled by said member for rotation and extending in an axial direction from the inlet passage to said exhaust passage, control ports provided by the valve and connecting with the inlet passage, other control ports provided by the valve and connecting with the exhaust passage, a plurality of ducts formed in the member and having associated relation at one end with the said control ports respectively, and at their other ends having connection with certain ends of the operating piston chamber, and certain of said ducts having connection with the end of the ram piston chambers respectively.

2. In a hydraulic booster, a housing member having an inlet passage connecting with a source of fluid pressure, an exhaust passage connecting with an exhaust line, and a high pressure delivery line connecting with an outlet passage for high pressure fluid, a differential piston with the member mounted thereby for reciprocating movement, said differential piston including a main operating piston having reciprocating movement within a chamber provided therefor by said member and ram pistons extending from each end of the main piston and which move in chambers respectively also provided by said member, a passage in the member associated with each ram piston chamber at the end thereof and connecting with said outlet passage for delivering high pressure fluid to the delivery line, a distributor valve journaled by said member for rotation and extending in an axial direction from the inlet passage to said exhaust passage, control ports provided by the valve, being located dia-

metrically of the same and connecting with the inlet passage, other control ports provided by the valve, being located diametrically of the same but displaced ninety degrees with respect to the first mentioned control ports and connecting with the exhaust passage, a plurality of ducts formed in the member and having associated relation at one end with the said control ports respectively, and at their other ends connecting with certain ends of the operating piston chamber, and certain of said ducts having connection with the end of the ram piston chambers respectively.

3. A hydraulic booster as defined by claim 1 additionally including a check valve adjacent and in communicating relation with the end of each ram piston chamber between the same and the passage associated therewith.

4. An hydraulic booster as defined by claim 1 additionally including a pair of check valves in spaced relation adjacent each ram piston chamber and in communicating relation therewith, one check valve in each pair being located between its respective chamber and the duct connecting therewith, and the other check valve of each pair being located between its respective chamber and the passage associated therewith.

5. In a hydraulic booster, a housing member having an inlet passage connecting with a source of fluid under pressure, an exhaust passage connecting with an exhaust line, and an outlet passage connecting with a high pressure delivery line, a differential piston within the member mounted thereby for reciprocating movement, said differential piston including a main operating piston having reciprocating movement within a chamber of greater length than the same and provided therefor by said member, and including ram pistons extending from each end of the main piston and which move in chambers respectively also of greater length than the respective ram piston and provided therefor by said member, a passage formed in the member for each ram piston chamber having connection with the end of its ram piston chamber and connecting with the outlet passage, each said passage delivering fluid to the outlet passage after compression of the same to a high pressure by its ram piston, at least one duct formed in the member for each ram piston chamber and connecting with the end of the same for admitting the fluid under pressure to the chamber, other ducts in the member having connecting relation respectively with the ends of the main piston chamber for alternately admitting and exhausting said pressure fluid whereby to produce reciprocating movement of the main operating piston and said ram pistons, and means controlling the admission of the pressure fluid to said ducts for delivery to the ram piston chambers and main operating piston chamber and exhausting of the pressure fluid from the latter chamber, said means including a distributor valve journalled by the member and having control ports connecting with the inlet passage and other control ports connecting with the exhaust passage.

6. An hydraulic booster as defined by claim 5 additionally including a check valve adjacent and in communicating relation with the end of each ram piston chamber between the same and the passage for said chamber.

7. A hydraulic booster as defined by claim 5 additionally including a pair of check valves in spaced relation adjacent each ram piston chamber and in communicating relation therewith, one check valve in each pair being located be-

tween its respective chamber and the duct connecting therewith, and the other check valve of each pair being located between its respective chamber and the passage for said chamber.

8. In a hydraulic booster, in combination, a differential piston mounted for reciprocating movement, said piston including a main operating piston and a ram piston extending from each end of the said main piston and of less diameter than the main piston, a main piston chamber and ram piston chambers associated therewith, said main and ram pistons having location within said chambers respectively, each ram piston chamber extending from its end of the main piston chamber, mechanism for effecting reciprocating strokes of the differential piston including means for delivering a fluid under pressure to either end of the main piston chamber, means for simultaneously discharging the fluid from the opposite end of the chamber, and means for also delivering a fluid under pressure to the respective rear ram piston chamber behind the ram piston thereof, whereby the forward ram piston is caused to compress the fluid within its chamber to a pressure higher than the initial pressure of the fluid, said mechanism including a rotary distributor valve having a controlling operation by reason of its rotation for controlling the delivery to and discharge from the various chambers of said fluid under pressure.

9. In a hydraulic booster, in combination, a differential piston mounted for reciprocating movement, said piston including a main operating piston and a ram piston extending from each end of the said main piston and of less diameter than the main piston, a main piston chamber and ram piston chambers associated therewith, said main and ram pistons having location within said chambers respectively, each ram piston chamber extending from its end of the main piston chamber, a pair of check valves at the outer end of each ram piston chamber for controlling the delivery to and exit from said chamber of a fluid, mechanism for effecting reciprocating strokes of the differential piston including means for delivering a fluid under pressure to either end of the main piston chamber, means for simultaneously discharging the fluid from the opposite end of the chamber, and means for also delivering a fluid under pressure to the respective rear ram piston chamber behind the ram piston thereof, whereby the forward ram piston is caused to compress the fluid within its chamber to a pressure depending on the setting of the check valve controlling the exit of the fluid from the chamber, said mechanism including a rotary distributor valve having a controlling operation by reason of its rotation for controlling the delivery to and discharge from the various chambers of said fluid under pressure.

10. In an hydraulic transformer having an inlet for supplying a low pressure oil thereto, a low pressure oil outlet, and a high pressure oil outlet for delivering oil at a higher pressure, a double ended reciprocating piston provided by said transformer for pumping said high pressure oil by the to and fro strokes of said piston, whereby the flow of both high and low pressure oil momentarily ceases when the reciprocating piston reaches the end of its stroke in either direction, and an auxiliary piston assembly for counteracting any rise in pressure of the oil in the low pressure oil inlet and any drop in pressure of the oil in the high pressure oil outlet caused by said stoppage in the flow of oil, said auxiliary piston assembly having

11

connected relation with both the low pressure oil inlet and the high pressure oil outlet and including a double-ended piston having a large diameter end and a small diameter end and subjected to the low and high pressure oil at the ends respectively.

11. In an hydraulic transformer having an inlet for supplying a low pressure oil thereto, a low pressure oil outlet, and a high pressure oil outlet for delivering oil at a higher pressure, a double ended, differential piston mounted for reciprocation by said transformer for pumping said high pressure oil by the to and fro strokes of said piston, whereby the flow of both high and low pressure oil momentarily ceases when the reciprocating piston reaches the end of its stroke in either direction, and an auxiliary piston assembly for counteracting any rise in pressure of the oil in the low pressure oil inlet and any drop in pressure of the oil in the high pressure oil outlet caused by said stoppage in the flow of oil, said auxiliary piston assembly having connected relation with both the low pressure oil inlet and the high pressure oil outlet and including an auxiliary piston having a large diameter end subjected to the low pressure oil and a small diameter end subjected to the high pressure oil, and said auxiliary piston having a non-pumping action.

12. In an hydraulic transformer for increasing the pressure of a fluid medium delivered thereto and wherein the volume of the high pressure medium compared to the volume of the low pressure medium entering the device is inversely proportional to the boost in pressure, the combination with an inlet and an outlet for the low pressure medium, an outlet for said high pressure medium,

5

10

15
